HUB CAP SPINNER OR THE LIKE

Philip Garcia, Centerline, Mich., assignor to General Motors Corporation, Detroit, Mich., a corporation of Delaware

Filed Feb. 24, 1961, Ser. No. 64,047

Term of patent 7 years

(Cl. D14—30)

I claim:

The ornamental design for a hub cap spinner or the like, substantially as shown.
